CHAIR CONVERTIBLE TO A TABLE

Donato R. Rizzolo, Bloomfield, N. J.

Application November 23, 1945, Serial No. 630,313

3 Claims. (Cl. 155—43)

1

This invention relates to a convertible furniture piece; and the invention has reference, more particularly, to a novel chair structure which is convertible, by simple manipulation, to optionally provide a reclining chair, a couch or a table.

The invention has for an object to provide a simple and efficient convertible chair structure formed by a plurality of sections and a supporting leg structure therefor, said sections comprising a seat section, a back section and a leg rest section, and said sections being articulated or pivotally interconnected with each other and with the leg structure in such novel manner that swinging movements of the back section are automatically transmitted to the other sections, whereby to dispose said sections in various selected relative positions adapted to optionally provide a reclining chair arrangement thereof, a substantially flatly extended couch-like arrangement thereof, or a folded arrangement thereof wherein the back section is disposed relative to the supporting leg structure and above the other folded sections so as to provide a table arrangement.

The invention has for another object to provide a novel chair structure, characterized as above stated, wherein side or arm rest members are arranged so as to be immovably supported by the leg structure, and wherein the articulated back, seat and leg-rest sections are pivotally suspended from said side or arm rest members.

Another object of the invention is to provide a novel convertible chair structure, characterized as above stated, wherein the foldable articulated sections and parts thereof are separable from the supporting leg structure so as to be removable therefrom, whereby said sections and parts and said leg structure, when separated, may be respectively collapsed and reduced to comparatively small bulk for storage or for packing into a suitable portable carrying means by which the chair structure may be conveniently transported if desired.

Other objects of this invention, not at this time more particularly enumerated, will be understood from the following detailed description of the same.

An illustrative embodiment of the invention is shown in the accompanying drawings, in which:

Fig. 1 is a side elevational view of a convertible chair structure made according to this invention, the same being arranged with its articulated sections as disposed to provide an upright or straight backed chair; Fig. 2 is a longitudinal

sectional view of the chair structure showing its articulated sections as disposed to provide a reclining chair; Fig. 3 is a similar longitudinal sectional view showing the articulated sections of the chair structure as disposed to provide a substantially flatly extended couch-like arrangement thereof; Fig. 4 is also a longitudinal sectional view showing the articulated sections of the chair structure as disposed to provide a table arrangement thereof; and Fig. 5 is a transverse vertical sectional view, taken on line 5—5 in Fig. 4.

Similar characters of reference are employed in the hereinabove described views, to indicate corresponding parts.

Referring to the drawings, the illustrative embodiment of the convertible chair structure of this invention, as therein shown, comprises a pair of immovably supported, laterally spaced apart, side members 10, preferably so formed that they may serve as arm rests. These side members or arm rests 10 are adapted to be mounted on a supporting leg structure. Preferably said leg structure is of collapsible construction, and arranged so as to be detachably connected with said side members or arm rests 10 in supporting relation thereto. One construction and arrangement of collapsible leg structure, as shown, comprises pairs of crossed leg members 11 and 12, pivotally joined at 13, so as to be capable of being folded together in substantially parallelly aligned relation. The upper end of the inner leg member 11 of each pair of leg members, when the latter are extended to operative relation, is adapted to abut the under side or edge of a side member or arm rest 10. Suitable releasable fastening means, such e. g. as the hook and stud means 14 (see Fig. 1), are provided for detachably securing said leg members 11 in the described supporting relation to the side members or arm rests 10. The upper end of the outer leg member 12 of each pair of leg members, when said leg members are extended to operative relation, is adapted to lap the outer side or face of a side member or arm rest 10. Suitable releasable fastening means, such e. g. as the stud and wing-nut means 15 (see Fig. 1), are provided for detachably securing said leg members 12 in the described supporting relation to the side members or arm rests 10. A cross-tie or bar 13' is secured to and between the rearwardly extending lower portions of corresponding leg members of said pairs thereof, as e. g. between such portions of the leg members 12.

The articulated movable sections of the chair structure comprise a seat section 16, a back section 17, and a leg rest section 18, the latter preferably terminating in a foot rest section 19. The rearward end of the seat section 16 is hingedly connected at 20 with the lower extremity of the back section 17. Said back section 17 is fulcrumed, at a point upwardly spaced from its hinged connection 20 with said seat section 16, by hinge or pivotal connections 21 with the rearward ends of the side members or arm rests 10. The forward end of the seat section 16 is suspended from the forward ends of the side members or arm rests 10 by swingable links 22. The upper ends of said links 22 are respectively pivotally connected at 23 with the forward ends of said side members or arm rests 10, and the lower ends of said links 22 are respectively pivotally connected at 24 with the respective opposite sides of the forward end of said seat section 16. By the described arrangement, that portion of the back section 17 which extends between its hinge or pivotal connections 21 with the rearward ends of the side members or arm rests 10 and its hinge connection 20 with the rearward end of the seat section 16, provides a swingable rearward linkage 22' cooperative with the swingable forward linkage provided by the links 22, whereby the seat section 16 is swingably suspended from the side members or arm rests 10, while that portion of the back section 17, which extends above the hinge or pivotal connections 21 with the rearward ends of the side members or arm rests 10, provides a power applying leverage for transmitting to the thus suspended seat section 16 required forward and back swinging movements when adjusting said back and seat sections to various desired positions adapted to optionally convert the chair structure to reclining chair, couch or table arrangement.

The upper or inner end of the leg rest section 18 is hingedly connected, also at 24, with the forward end of said seat section 16, but is so fixed to the links 22 as to constitute in effect a rigid extension thereof. Pivotally connected respectively with opposite sides of the forward end portion of the seat section 16, at points 25 rearwardly spaced from the leg rest hinge connection at 24, are the upper ends of lever bars 26 which extend downwardly in spaced relation and more or less parallel to the sides of said leg rest section 18. The lower ends of said lever bars 26 and the lower end of said leg rest section 18 are interconnected by coupling links 27 pivotally related thereto by the respective hinge connections 28 and 29. Integral with the forward ends of said coupling links 27 are extensions 30 thereof which project beyond the lower or outer end of said leg rest section 18. To and between these link extensions 30 is affixed the foot rest section 19, whereby the same is articulately related to the lower or outer end of said leg rest section 18.

In an illustrative arrangement of the above described sections and their articulating connections, as shown, said sections are preferably, although not necessarily, combined with rigid metallic frame portions, of either flat or tubular stock, to which and between which the section bodies may be suitably secured. Such frame portions may comprise frame pieces 31 to which are fixedly secured the side members or arm rests 10, which frame pieces terminate in the hinging or pivotal connections 21 and 23; frame pieces 32 to which are fixedly secured the sides of the

seat section 16, which frame pieces terminate in the hinging or pivotal connections 20 and 24; frame pieces 33 to which are fixedly secured sides of the back section 17, the lower ends of which 5 frame pieces terminate in the hinging or pivotal connection 20; and frame pieces 34 to which are fixedly secured the sides of the leg rest section 18; said frame pieces 34 preferably being rigid extensions of the links 22.

10 The seat, back, leg rest sections 16, 17 and 18 and the foot rest section 19 if desired, may comprise suitably upholstered bodies, or optionally may comprise canvas or like bodies suitably attached to and between the frame pieces.

15 Affixed to the rear face of the back section 17 is a table top section 35 made of suitable material and of desired peripheral shape or design.

20 In the use and operation of the novel convertible chair structure, to dispose the body sections in position to form a normal straight backed chair (see Fig. 1), the back section 17 is swung forwardly to upright position about the hinge or pivotal connections 21, whereby the rearward linkage 22' is rearwardly swung relative to the 25 supporting leg structure and fixed side members or arm rests 10, thus producing a rearward movement of the linkage suspended seat section 16. Since the leg rest section 18 in effect constitutes a rigid extension of the links 22, the rearward 30 swinging movement of the latter, which accompanies said rearward movement of the seat section 16, produces a rearward and downward swinging movement of the leg rest section 18, whereby to dispose the same in a substantially 35 perpendicular normal position. The rearward swinging movement of the leg rest section 18 is transmitted through the links 27 to the lever bars 26, thus causing the latter, as they swing about their fulcrum points 25, to exert a downward 40 thrust upon said links 27 operative to swing the same downwardly about their pivotal connections 29 with the lower end of the leg rest section 18, and thereby simultaneously swinging the extensions 30 of said links 27 with the foot rest 45 19 upwardly, so as to dispose the foot rest section 19 in a substantially horizontal plane, substantially parallel to the plane of the seat section 16, and thus substantially right angularly to the perpendicularly disposed leg rest section 18.

50 From the above described straight backed chair arrangement, the body sections may be moved into reclining chair forming positions of selected inclination, and finally to couch forming arrangement (see Figs. 2 and 3). This is accomplished by swinging the back section 17 rearwardly about the hinge or pivotal connections 21. By so doing, the rearward linkage 22' is forwardly swung relative to the supporting leg structure and fixed side members or arm rests 10, thus producing a forward movement of the linkage suspended seat section 16, with accompanying forward swinging movements of the links 22 and leg rest section 18, whereby, as the back section swings downwardly to a given upwardly 55 inclined position, said leg rest 18 will swing upwardly to a substantially corresponding downwardly inclined position (see Fig. 2). At the same time the upward swinging movement of the leg rest structure 18 is transmitted through the links 27 to the lever bars 26, thus causing the latter, as they swing about their fulcrum points 25, to exert an upward pull upon said links 27 operative to swing the same upwardly about their 60 pivotal connections 29 with the lower end of the leg rest section 18, and thereby simultaneously 65

swing the extensions 30 of said links 27 downwardly, so as to maintain the foot rest section in substantially horizontal plane or plane substantially parallel to the seat section 16 (again see Fig. 2). The back section 17 may be rearwardly and downwardly swung to substantially horizontal plane, i. e. more or less into the plane of the seat section 16, with accompanying upward swing of the leg rest section 18 and associated movement of the foot rest section 19, so that these latter sections are also finally brought into substantially horizontal plane, in which condition all the body sections are brought into more or less common plane, whereby to convert the chair structure to the couch arrangement thereof (see Fig. 3).

The described relative movements of the body sections are so mutually balanced, that conversion of the chair structure from straight backed chair arrangement through reclining chair arrangements to a final couch forming arrangement may be accomplished simply by the occupant assuming a desired reclining position, since the balance of the sections permits the same to automatically follow the movement of the occupant's body. For example, in changing from upright to reclining position the occupant leans back thereby exerting back swinging pressure upon the back section 17 with accompanying forward shifting movement of the seat section 16 and resultant upswinging movement of the leg rest section. To return the chair structure to upright condition, the occupant merely leans forward or rises from the waist, thus removing back swinging pressure from the back section 17 and transferring body weight to the seat section 16, which swings or forces the latter downward, thus not only effecting accompanying down swinging movement of the leg rest section 18, but also compelling the back section 17 to maintain pressure against the back of the occupant.

It may be desired to releasably secure the chair structure in a desired reclining or couch arrangement, so as to prevent the above described automatic movements of the body sections in response to movements of the occupant's body. Means for this purpose may take various forms and may be variously related to relatively movable parts of the chair structure. An illustrative form of means for such purpose, as shown, comprises a slotted fastener link 36 pivotally anchored by one end to a fixed point, as e. g. the pivotal connection 24. Said fastener link 36 is adapted to extend to and across the adjacent lever bar 26, and the latter is equipped with a stud and thumb-nut fastener means 37 engaged through the slot of said link 36. When the body sections have been positioned in desired relative disposition, the stud and thumb-nut fastener 37 may be tightened so as to bind the fastener link 36 to the lever bar 26, thus preventing operative movements thereof, and consequently of the entire articulated structure of which it forms a part.

When the chair structure is not desired to be occupied, the same may be quickly and easily converted into a serviceable table arrangement. This is done merely by swinging the back section 17 forwardly from its upright position and downwardly so as to rest upon the side members or arm rests 10, and thus in horizontal plane, with its table top portion 35 upwardly presented. Such forward and downward swinging movement of the back section 17, produces a rearward and upward movement of the seat section 16 to dispose the same in underlying relation to the downswung back section, while at the same time, the

rearward and upward movement of the seat section 16, produces through the induced movements of links 22 and lever bars 26 a rearward and upward swinging movement of the leg rest section 18, and a forward and upward swinging movement of the foot rest section 19, so that these latter sections are likewise in-folded beneath the seat section and lowered back section (see Figs. 4 and 5).

Having now described my invention, I claim:

1. A furniture piece adapted to be optionally converted to chair or table form comprising a leg structure, laterally spaced stationary side members supported by said leg structure, body sections including a back section and a seat section, each said section being of width less than the spaced separation of said side members, suspension link means pivotally connected with and extending between the forward ends of said side members and the forward end of said seat section, a table top panel of a width exceeding the spaced separation of said side members, said panel being affixed to the rear face of the back section, joint means extending rearwardly from the side members by which the back section is pivotally connected therewith at points upwardly spaced from the lower end of the latter, and additional joint means for pivotally interconnecting the rearward end of the seat section with the lower end of the back section in spaced apart relation, said latter joint means comprising joint portions projecting rearwardly and upwardly from the seat section and pivotally joined to forwardly projecting joint portions extending from the lower end of the back section, whereby said back section may be swung forward and downwardly into horizontal superposed relation to the simultaneously lifted seat section with the table top panel supported by and across said side members to convert the furniture piece to table form.

2. A furniture piece adapted to be optionally converted to chair or table form as defined in claim 1, wherein the body sections further include a leg rest section, a third joint means for pivotally interconnecting the upper end of the leg rest section to the forward end of the seat section in spaced apart relation, said third joint means comprising downwardly projected portions extending from the forward end of the seat section and pivotally joined to the upper end portion of said leg rest section, whereby said leg rest section may be swung rearward into underlying relation to said seat section when the furniture piece is converted to table form, lever bar means pivotally connected with the sides of the seat section at points spaced rearwardly from the forward end thereof, said lever bar means extending substantially parallel to the leg rest section, link means pivotally interconnected between the lower ends of the leg rest section and said lever bar means, and means to releasably secure said body sections in selected relatively adjusted disposition comprising a fastener link means pivoted by one end to joint means intermediate the spaced ends of said seat and leg rest sections, said fastener link means intersecting said lever bar means, and manipulatable fastener means for releasably securing said link means to said lever bar means.

3. A furniture piece adapted to be optionally converted to chair or table form comprising a leg structure, laterally spaced stationary side members supported by said leg structure, body sections including a table top and back section and a seat section, said seat section being of

width less than and the table top being of a width greater than the spaced separation of said side members, suspension link means pivotally connected with and extending between the forward ends of said side members and the forward end of said seat section, joint means extending rearwardly from the side members by which the table top and back section is pivotally connected therewith at points upwardly spaced from the lower end of the latter, and additional joint means for pivotally interconnecting the rearward end of the seat section with the lower end portion of the table top and back section, said latter joint means comprising joint portions projecting rearwardly and upwardly from the seat section and pivotally joined to forwardly projecting joint portions extending from the lower end portion of the table top and back section at points spaced below said first mentioned joint means, whereby said table top and back section may be swung forward and downwardly from erect chair back forming position into horizontal superposed rela-

tion to the simultaneously lifted seat section and so as to be supported by and across said side members to convert the furniture piece to table form.
